SEWING MACHINE

Raymond F. List and Walter A. Smith, Belvidere,
Ill., assignors to National Sewing Machine
Company, Belvidere, Ill., a Corporation of
Illinois

Application October 12, 1931. Serial No. 568,332

10 Claims. (Cl. 45—27)

This invention relates to sewing machines and more particularly to treadle operated sewing machines. Other embodiments of this invention have heretofore been described and claimed in 5 our co-pending application Serial No. 562,676 filed September 14, 1931.

The main object of the invention is to produce a treadle operated sewing machine which can be manufactured at a substantially lower cost than 10 can a motor driven machine and which will embody certain features of advantage found in motor driven machines and not heretofore available in treadle operated machines, these features including compactness, attractive appearance and 15 means for enclosing the operative parts in such way that the machine will be acceptable as a piece of furniture in a living room.

In all treadle operated machines on the market, the side frame castings, the treadle, the pitman 20 shaft, a large pulley wheel and a belt running to the drive shaft of the stitch-forming mechanism are fully exposed and the machines as a whole are relatively large and unattractive in appearance. 25 It is our purpose to disguise a treadle operated sewing machine in such manner as to make the same attractive in appearance as an article of furniture.

Motor driven sewing machines have been enclosed in attractive cabinets, and because of the 30 absence of treads and power-transmitting mechanism, no difficult problems were involved in covering the utilitarian features of the construction and making the machine function as a piece of living room furniture when not being 35 used for sewing. However, on account of the cost of production, motor driven machines are not available to many users of sewing machines, and one of the objects of this invention is to produce, at low cost, a machine having the desirable features above mentioned.

One of the specific objects of this invention is to make the treadle and a part of the pitman shaft removable from the rest of the machine and to pivotally connect the pitman to the treadle 45 in such manner that the pitman may be swung into a position closely adjacent to the treadle and to extend longitudinally of the treadle. This arrangement facilitates storing of the disconnected treadle and pitman when the machine is not in use.

Another specific object is to provide means for disengageably connecting the treadle to the cabinet, which means permits of the substitution of a furniture cross bar for the treadle when the latter has been removed.

The objects of the present invention are accomplished by providing means, very compact in form, for transmitting power from the treadle to the stitch-forming mechanism, and locating the same entirely within a drop head cabinet which 60 is supported on conventional table legs, and, further, by providing a removable treadle disengageably connected to the means for transmitting power to the stitch-forming mechanism. Other objects and advantages will appear from 65 the following specification.

In the drawings:

Fig. 1 is a longitudinal vertical sectional view 70 through a sewing machine embodying our invention.

Fig. 2 is a transverse vertical sectional view 75 taken on the line 2—2 of Fig. 1.

Fig. 3 is a horizontal sectional view taken on the line 3—3 of Fig. 1, looking downwardly as indicated by the arrows.

Fig. 4 is a vertical sectional view taken on the line 4—4 of Fig. 1.

Fig. 5 is a vertical sectional view taken on the line 5—5 of Fig. 1, showing the means for disengageably connecting the treadle to a fixed part 80 of the cabinet.

Fig. 6 is a vertical sectional view taken on the line 6—6 of Fig. 5.

Fig. 7 is a horizontal sectional view taken on the line 7—7 of Fig. 5.

Fig. 8 is a perspective view of one of the cabinet 85 side bars to which is attached one member of the means for disengageably connecting the treadle to the cabinet.

Fig. 9 is a vertical sectional view through the 90 lower part of the cabinet support showing the side bars in section and the cross bar in elevation, the cross bar having been substituted for the removed treadle.

Fig. 10 is a horizontal section taken on the line 95 10—10 of Fig. 9.

Fig. 11 is a perspective view of the cross bar shown in Figs. 9 and 10.

In that embodiment of the invention shown in the drawings, 10 indicates legs, four in number, 100 for supporting a drop head cabinet 11. The cabinet consists of a back wall 12 and side walls 13 and 14 fixedly secured to the legs 10. A front wall or door 15 is hingedly secured along one side edge to one of the legs 10. A table top 16, provided with an elongated opening of about the size of the bed plate of the sewing head, is fixedly secured to the top edges of the back and side walls of the cabinet. Forwardly of the opening in the table top 16 is a hinged bib 17 which is raised 110

while the sewing head is lifted, and then lowered to support the head. The bottom 18 of the drop head cabinet is made of a curved piece of wood or other suitable material and is not as wide as the space between the side walls 13 and 14. Said bottom 18 is fixed to the bottom of the back wall 12 and is curved and inclined upwardly toward the front where it joins the longitudinally extending front beam 19. Hingedly secured to the side of the table top 16 is a table member 20 which overlies the top 16 when the head has been lowered and the machine is not in use. The door 15 may be opened when the machine is being used, the shape of the bottom wall 18 being such as to accommodate the knees of the user in front of the machine, while the inside of the drop head cabinet is just large enough to receive the sewing head when the machine is not in use. A receptacle 21 may be secured to the bottom of the inner surface of the door 15.

A conventional sewing machine head 22 is indicated in Fig. 1, the same being supported on a bed plate, not shown. The bed plate is hingedly secured to the table top 16 along its margin 24 adjacent the opening in the top 16 through which the bed plate and sewing head may be dropped into the cabinet when the bib 17 has been raised.

In the bottom of the cabinet, extending longitudinally adjacent the rear wall 12, is a horizontally disposed shaft 25, rotatably mounted in bearings 26 secured to the inner surfaces of the side walls 13 and 14. A pulley wheel 27 is fixedly secured to the shaft 25 adjacent one side wall and a similar pulley wheel 28 is fixedly secured to the shaft 25 adjacent the other side wall of the cabinet. The pulley 27 is connected by a flexible belt 29 to the combination pulley and fly wheel 30 on the horizontal shaft of the sewing machine head 22. The top 16 is apertured at 31, to receive the belt 29.

The other pulley 28 is operatively connected with a grooved disc or pulley wheel 34 rotatably mounted on the stub shaft 35 fixed in the side wall 14 of the cabinet 11. A flexible belt 36 operatively connects the pulleys 28 and 34. The wheel 34 is considerably larger than the pulley 28 and the open bottom of the cabinet at one side accommodates the pulley 34 as well as the upper section 37 of a two piece pitman shaft 37-38. The shaft section 37 is rotatably mounted on the hub 39 which extends laterally from one side of the wheel 34, being formed with an eye 40 at its upper end through which said hub 39 extends.

The lower end of the pitman shaft section 38 is located between a pair of apertured ears 41 which extend radially from a bearing 42. The end of the shaft 38 is pivotally connected to said ears 41 by a pin 44. A bolt 43 extends through the bearing 42 and the bifurcated member 45 of the treadle 46, and is held in position by nuts 47. This arrangement provides a pivotal connection between the pitman shaft 38 and treadle 46, through the bolt 43, and a second pivotal connection between the pitman shaft 38 and the bearing 42, through the pin 44. This permits the pitman shaft section 38, when disconnected from the part 37, to be swung into the dotted line position of Fig. 3, so that it extends longitudinally of the treadle and closely adjacent to the rear edge of the same, and facilitates storing of the treadle and pitman shaft section 38 when the same have been removed from the machine.

The upper end of the pitman shaft section 38 may be disengageably connected to the pitman shaft section 37 in any suitable manner. The

part 37 depends from the wheel 34 a sufficient distance to permit attachment to the part 38 externally of the cabinet. As shown, said section 38 is provided with an enlarged hollow upper end adapted to receive the lower end of the member 37. A set screw 48 engages an aperture or depression in the pitman shaft 37 and holds the shaft sections together in alignment. Other means for disengageably connecting the shaft sections may be used.

Referring now to the means for disengageably connecting the treadle to the cabinet support, the fixed side bars 49 are provided on their inner surfaces with a fixture which is shown in perspective in Fig. 8 and in sectional views in Figs. 6 and 7. Said fixture comprises a pair of upright arms 50 and a cross piece 51 which joins the lower ends of said arms 50. Preferably the cross piece 51 has a shoulder 52 on its rear surface for abutting against the lower edge of the cabinet side bar 49. The upright arms 50 are cut away at their rearward, proximate edges as indicated at 53 in Fig. 7. By reference to Figs. 6 and 8 it will be seen that the cut away portion 53 does not extend to the cross piece 51, a shoulder 54 being formed slightly above said cross piece for a purpose to be described. The fixture 50, 51 is secured to the cabinet side bar 49 by countersunk screws 55. The shape of the parts 50 and 51 is such that a rectangularly shaped slot, open at the top, is formed in said fixture.

The treadle-carrying rod 56 is mounted, at each end, in the lower end 57 of an elongated plate 58. On its rear surface, that is, the surface which is not exposed when the plate is in operative position, the plate 58 has formed on it a rearwardly projecting, rectangularly shaped lug 59 adapted to fit into the recess formed by the members 50 and 51, the lower surface of the lug 59 resting on top of the cross piece 51. Since the distance between the fixtures secured to the side bars 49 is the same as the combined length of the treadle rod 56 and attached plates 58, said plates 58 will be firmly held between said fixture arms 50 when the lugs 59 are slipped downwardly into the recesses to seat on the cross pieces 51. The length of the plate 58 is such that the cabinet side bars 49 may be in normal location above the floor and yet the treadle rod 56 will be supported in a plane sufficiently low to make operation of the treadle 46 convenient for the operator. The treadle, plates 58 and pitman section 38 are easily removed, as a unit, by loosening the set screw 48, moving the shaft 38 downwardly relatively to the member 37, and sliding the plates 58 upwardly to disengage the same from the fixture 50-51.

When the treadle unit has been removed, a conventional furniture cross bar 60 may be substituted for the treadle, for the purpose of improving the appearance of the cabinet and its supports as a piece of furniture. The cross bar 60 has secured to it at each end a plate 61 which is slightly wider than the bar 60 and of such size and shape that it will fit into the recess 53 formed by cutting away the rear surface of the arms 50, the lower edge 62 of the plate 61 resting on the shoulder 54 on the rear of said arms 50. The dimensions of the cross bar 60 are such that it fits between the arms 50 and rests on the edge of the cross piece 51. When in position the cross bar 60 partially hides the fixture on the side bars, strengthens the construction of the cabinet, as a whole, and improves its appearance.

Changes may be made in details of construc-

tion without departing from the scope of our invention and we do not intend to be limited to the exact form shown and described, except as set forth in the appended claims.

5 We claim:—

1. In a treadle operated sewing machine provided with a treadle and spaced apart supports for carrying the sewing mechanism, means for disengageably mounting the treadle in said supports, said means comprising a slotted fixture secured to each of said supports and a fixture-engaging member mounted on each end of the treadle rod.

15 2. In a treadle operated sewing machine provided with a treadle and spaced apart supports for carrying the sewing mechanism, means for disengageably mounting the treadle in said supports, said means comprising a fixture secured to each of said supports and a fixture-engaging member mounted on each end of the treadle rod, the fixture being slotted downwardly from its top, and the fixture-engaging member having a lug formed at its upper end for entering said slot.

25 3. In a treadle operated sewing machine provided with a treadle and spaced apart supports for carrying the sewing mechanism, means for disengageably mounting the treadle in said supports, said means comprising a fixture secured to each of said supports and a fixture-engaging member mounted on each end of the treadle rod, the fixture consisting of two spaced apart upright arms connected at their lower ends by a cross piece.

35 4. In a treadle operated sewing machine provided with a treadle and spaced apart supports for carrying the sewing mechanism, means for disengageably mounting the treadle in said supports, said means comprising a fixture secured to each of said supports and a fixture-engaging member mounted on each end of the treadle rod, the fixture consisting of two spaced apart upright arms connected at their lower ends by a cross piece, and the fixture-engaging member having a lug on one side for fitting between the arms and bearing on said cross piece.

50 5. In a treadle operated sewing machine provided with a treadle and spaced apart supports for carrying the sewing mechanism, means for disengageably mounting the treadle in said supports, said means comprising a fixture secured to each of said supports and a fixture-engaging member mounted on each end of the treadle rod, the fixture being slotted between its side margins for receiving the fixture-engaging member on the treadle, and cut away on that side adjacent the support to provide a space between the fixture and the support for the reception of a complementally shaped part of a furniture cross bar when the latter is substituted for the treadle.

6. In a treadle operated sewing machine provided with a treadle and spaced apart supports for carrying the sewing mechanism, means for disengageably mounting the treadle in said supports, said means comprising a fixture secured to each of said supports and a fixture-engaging member mounted on each end of the treadle rod, the fixture-engaging member being an elongated plate having fixture-engaging means formed on its upper end and a treadle rod bearing on its lower end.

80 7. A treadle operated, cabinet type sewing machine comprising a sewing head mounted on the cabinet, power transmitting mechanism in the cabinet, supports for the cabinet, a treadle, means for detachably connecting the treadle to the power transmitting mechanism, and means for disengageably mounting the treadle in the cabinet supports, said means comprising a pair of slotted fixtures secured to the cabinet supports, and a fixture-engaging plate having flanges mounted on each end of the treadle rod.

90 8. A treadle operated, cabinet type sewing machine comprising a sewing head mounted on the cabinet, power transmitting mechanism in the cabinet, supports for the cabinet, a treadle, a pitman shaft, means for detachably connecting the pitman shaft to the power transmitting mechanism, a pivotal connection between the pitman shaft and the treadle, consisting of a bifurcated projection on the treadle, a bearing carrying a pair of apertured ears, a bolt pivotally connecting the treadle and bearing, a pin pivotally connecting the pitman shaft and the bearing ears, said pin being at a right angle to said bolt.

100 9. In a sewing machine, a removable treadle unit consisting of a treadle, a treadle rod, a pitman shaft pivotally connected to the treadle and carrying on its free end means for detachable connection with the sewing machine mechanism, and a plate mounted on each end of the treadle rod and carrying means for disengageably co-operating with a fixed part of the machine when the treadle is in operative position.

115 10. In a sewing machine, a removable treadle unit consisting of a treadle rod, a treadle mounted on the rod, and a pitman shaft pivotally connected to the treadle, the pivotal connection between the pitman shaft and treadle including a bearing, a bolt pivotally connecting the bearing to the treadle, said bolt extending longitudinally of the treadle, and a pin extending at right angles to the bolt and pivotally connecting the pitman shaft to said bearing, whereby the pitman shaft may be moved both longitudinally and transversely of the treadle.
